[57] CLAIM

The ornamental design for a quilting ruler, as shown
and described.

DESCRIPTION

FIG. 1 is a top, front, and right side perspective view of
a quilting ruler showing my new design;

FIG. 2 is a right side elevational view, the left side
elevational view being a mirror image; and

FIG. 3 is a top plan view, thereof, the bottom plan view
being flat, plain, and unornamented.
